ELECTRICAL HEATING ELEMENT

Edwin L. Wiegand, Pittsburgh, Pa.

Application March 21, 1939, Serial No. 263,178

19 Claims. (Cl. 201—64)

My invention relates to electrical heating elements of the type comprising a resistor disposed within and insulated from a tubular metallic sheath. The principal object of my invention is to provide new and improved electrical heating elements of said type.

In the drawing accompanying this application, I have shown, for purposes of illustration, an electrical heating element of the aforesaid type, which may assume various forms and may be insulated in various ways, as will appear as the description of the invention proceeds, and in this drawing:

Figure 1 is a side elevation of an electrical heating element of the type in which the invention may be embodied,

Figure 2 is a longitudinal section of a portion of the heating element shown in Figure 1, and

Figures 3, 4, and 5 are sections taken along the lines 3—3, 4—4, and 5—5, of Figure 2, respectively, looking in the direction of the arrows.

The particular heating element shown in the drawing comprises an elongated tubular metallic sheath 20, in this instance of circular cross-sectional outline, in which is disposed a resistor 21, here shown as a helix of resistance wire. A lead-in conductor 22, here shown as comprising a lead-in wire 23 and a terminal 24, is provided. One end of the lead-in wire 23 is mechanically and electrically connected to an end of the resistor 21, and the other end of the lead-in wire is mechanically and electrically connected to the terminal 24. The terminal 24 is here shown as generally cylindrical, and as extending a desired distance into the open end 25 of the tubular sheath 20. The lead-in wire 23 is here shown as connected to the terminal 24 by the provision of a central, longitudinally extending hole 26 in the terminal 24 in which hole the lead-in wire 23 is disposed, and the end of the wire 23 may be fastened to the terminal 24 by swaging the terminal against and about the wire as indicated, at 27. The free end of the terminal 24 is here shown as provided with threads.

The terminal 24 is here shown as spaced and insulated from the inside of the tubular sheath by an insulating bushing 28. This bushing 28 may be made of a single piece of suitable insulating material, or it may be made built-up of laminae made of some integral material, such as mica or any other suitable material. The end portion of the sheath 20 is not subjected to very high temperatures so that fact may be taken into account in the selection of the material of the bushing 28. The sheath 20 may be swaged against and about the bushing 28, as indicated at 29.

The other end of the heating element is provided with a terminal 24a insulated from the

sheath 20 by a bushing 28a, as hereinbefore described in connection with the terminal 24 and bushing 28. The end of the resistor 21, opposite from that shown in Figure 2, may be connected by a lead-in wire (not shown), similar to the lead-in wire 23, to the terminal 24a, as already described in connection with the lead-in wire 23 and the terminal 24.

The heating element illustrated may be considered as comprising what may be termed a principal insulated zone *a* which extends from the inside of the bushing 28 to the inside of the bushing 28a. Within the sheath 20 in the zone *a* the resistor 21 and lead-in wire 23 are embedded in insulating material 30 which initially may be in a comminuted or powdered state, but which in the final condition of the heating element desirably is compacted to a hard dense mass. It will be understood that the initial form or state of the insulating material 30, in which it is introduced into the sheath 20, may be varied, and varied to suit any desired method of introducing it or the resistor 21, or both, into the sheath. The sheath 20 initially may be of a different form or size and may be brought to final condition by working, as by drawing and elongating, thus compressing and compacting the insulating material 30. On the other hand, the insulating material 30 may be compacted by vibration, or in any other desired and suitable way. Also, the sheath 20 need not be drawn and elongated, but initially may have the same general form as when the element is completed. It will be understood of course that even after the heating element is otherwise completed it may be bent so that its longitudinal axis is of a desired configuration; or it may have its cross-sectional outline altered, as by compression, or otherwise.

In general, the insulating material 30, in the zone *a* may, if desired, have mixed therewith a binding or cementing material, as clay, or any other suitable binder.

For the purpose of considering the invention in its more specific aspects, the zone *a* first may be considered as divided into a zone *c*, which is occupied by the resistor 21, and, as the ends of the zone *c* are spaced a desired and suitable distance from the ends of the sheath 20, this leaves a zone *b* between each end of the zone *c* and the respective ends of the sheath 20. The zone *c* is of course a high temperature zone and the insulating material in at least this zone should be a suitable refractory insulating material, for example, silica, or silicate, for example, zircon (zirconium silicate) or magnesium oxide, or aluminum oxide, or any refractory oxide or combination of refractory oxides, or any other suitable refractory insulating material, desirably of a mineral character, and desirably having good

heat-conducting properties. Crystalline oxides or silicates are desirable. As will appear, such materials need not however be confined to the zone *c*, although if crystalline magnesium oxide or any other unstable refractory insulating material, is utilized in the zone *c*, it should, in accordance with the present invention, not be used in the whole length of the zone *b*, as will further appear.

If the zone *c* is occupied by an unstable oxide such as crystalline magnesium oxide, then a portion of the length of the zone *b*, or the entire zone *b*, should comprise an insulating material which will serve to entrap moisture which may enter through the bushing, or between the bushing and the sheath. Thus, if desired, the entire zone *b* may comprise a stable oxide, or a stable silicate, desirably crystalline. By way of example, zircon, silica, aluminum oxide, or any other stable oxide or silicate may be utilized. It will be evident that the interposition of a zone of suitable length of such stable material between unstable crystalline magnesium oxide and an end of the sheath 20 will prevent such an amount of moisture as is likely to enter the end of the sheath under ordinary conditions from reaching the unstable material. Both the unstable and stable material will thus remain unchanged and the moisture entrapped by the stable material will be driven off by heat upon subsequent use of the heating element.

Under some conditions, by way of example, more severe conditions of use, I prefer to utilize an active sorbent material, that is, a material having active water absorbing capacity, or active water adsorbing capacity, in all of the zone *b* or a portion of the zone *b*. Such material, desirably of granular form, will sorb relatively large amounts of moisture, and the material may be brought to its original activated state upon heating.

In case an active sorbent material is used, activated alumina, or silica gel (activated silicon oxide), or any other suitable material of like nature may be used. It is necessary in selecting such a sorbent granular material to choose a material which does not alter physically when saturated or unsaturated and which may be reactivated by heat, desirably an infinite number of times, at operating temperatures which can normally be assigned to the portion of the heating element containing this material, in fact at the lowest temperature in the heating element. Its electrical resistivity must, of course, be suitably high. Such materials as activated alumina, silica gel, and the like, may be termed reversible sorbents, and may be described as having reversible water sorbing capacity. When a reversible sorbent is utilized, and if the zone *c* comprises an unstable material, such as crystalline magnesium oxide, the zone *b* may comprise a reversible sorbent, or the zone *b* may be divided into two zones *d* and *e*, the zone *d* comprising a reversible sorbent and the zone *e* comprising a stable refractory oxide or silicate, examples of which have been hereinbefore given. By way of example, the zone *c* may comprise crystalline magnesium oxide, the zone *e* may comprise zircon and the zone *d* may comprise activated alumina. On the other hand, a zone comprising a reversible sorbent may be utilized even though the zone *c* comprises a stable refractory insulating material. Thus, the zone *c* may comprise a stable refractory insulating material, preferably a stable crystalline oxide or silicate, and the zone *b* may

comprise a reversible sorbent; or the zone *c* may comprise a stable refractory insulating material, preferably a stable crystalline oxide or silicate, and the zone *e* may comprise stable refractory insulating material either the same as or different from the material in the zone *c*, and the zone *d* may comprise a reversible sorbent. It may be stated that even if the zone *c*, as well as the zone *e* comprises stable insulating material it is desirable to guard against the entrance of moisture which, either by reason of long inactivity of the heating element under unfavorable atmospheric conditions, or by reason of other conditions of use, may reach the material in which the resistor is embedded, and, upon connection of the heating element to a source of current, so as to at once operate it at full capacity, may result in rupture of the tubular sheath 20, or otherwise cause failure of the element. If the heating element contains an unstable refractory insulating material, protection against moisture is all the more important, since, for example, crystalline magnesium oxide will hydrate and swell in the presence of moisture and disruption of the sheath 20 may result, so that the heating element may be ruined for that reason alone, even before connection to a source of current. Some water, of course, may be driven off from hydrated magnesium oxide, in the range of temperatures attained in the heating element, but after hydration it cannot be regenerated by temperatures in that range. Moreover, after hydration, initially crystalline magnesium oxide is no longer crystalline. Accordingly, as distinguished from a stable insulating material, or as distinguished from a material having reversible water sorbing capacity, crystalline magnesium oxide is unstable, is irreversible, and has irreversible water sorbing capacity, under the conditions hereinbefore set forth. It will, therefore, be evident that, if the zone *c* comprises unstable insulating material, access of moisture thereto is undesirable whether the material swells upon hydration, or whether it loses certain physical properties, such as its crystalline nature, for example, or is otherwise undesirably altered.

It will be apparent from the foregoing that the length of any given insulation zone is not necessarily restricted to the examples of length given on the drawing. Thus, any zone may be longer or shorter than illustrated; or may even be merged entirely with another zone or zones, depending upon whether one or more different insulating materials are utilized as hereinbefore set forth.

From the foregoing it will be apparent to those skilled in the art that each of the disclosed embodiments of my invention provides a new and improved electrical heating element, and accordingly, each accomplishes the principal object of my invention. On the other hand, it also will be obvious to those skilled in the art that the disclosed embodiments of my invention may be variously changed and modified, or features thereof, singly or collectively, embodied in other combinations than those disclosed, without departing from the spirit of my invention, or sacrificing all of the advantages thereof, and that accordingly, the disclosure herein is illustrative only, and my invention is not limited thereto.

I claim:

1. An electrical heating element, comprising: a tubular metallic sheath; a resistor in a resistor zone within said sheath and having an end

spaced from an end of said sheath; a lead-in conductor in a terminal zone, extending into said end of said sheath longitudinally of said sheath and connected to said end of said resistor; and refractory electrical-insulating material, disposed within said sheath, in which said resistor is disposed, at least a transverse sectional portion of said terminal zone being occupied by a mass of particles of refractory-electrical-insulating material having desired stability in the presence of moisture and constituting barrier means for intercepting moisture, said barrier means comprising at least a substantial amount of refractory electrical-insulating material having reversible water sorbing capacity.

2. An electrical heating element, comprising: a tubular metallic sheath; a resistor in a resistor zone within said sheath and having an end spaced from an end of said sheath; a lead-in conductor in a terminal zone, extending into said end of said sheath longitudinally of said sheath and connected to said end of said resistor; and refractory electrical-insulating material, disposed within said sheath, in which said resistor is disposed, at least a transverse sectional portion of said terminal zone being occupied by a mass of particles of refractory electrical-insulating material having desired stability in the presence of moisture and constituting barrier means for intercepting moisture, said barrier means comprising at least a substantial amount of activated alumina.

3. An electrical heating element, comprising: a tubular metallic sheath; a resistor in a resistor zone within said sheath and having an end spaced from an end of said sheath; a lead-in conductor extending into said end of said sheath longitudinally of said sheath and connected to said end of said resistor; and refractory electrical-insulating material, disposed within said sheath, in which said resistor and said lead-in conductor are disposed, said material in at least a portion of said resistor zone comprising refractory electrical-insulating unstable material having irreversible water sorbing capacity, and at least a transverse sectional portion of an end zone extending from said end of said sheath to said unstable material being occupied by a mass of particles of refractory electrical-insulating material having desired stability in the presence of moisture and constituting barrier means for intercepting moisture, said barrier means comprising at least a substantial amount of refractory electrical-insulating material having reversible water sorbing capacity.

4. An electrical heating element, comprising: a tubular metallic sheath; a resistor in a resistor zone within said sheath and having an end spaced from an end of said sheath; a lead-in conductor extending into said end of said sheath longitudinally of said sheath and connected to said end of said resistor; and refractory electrical-insulating material, disposed within said sheath, in which said resistor and said lead-in conductor are disposed, said material in at least a portion of said resistor zone comprising refractory electrical-insulating unstable material having irreversible water sorbing capacity, and at least a transverse sectional portion of an end zone extending from said end of said sheath to said unstable material being occupied by a mass of particles of refractory electrical-insulating material having desired stability in the presence of moisture and constituting barrier means for intercepting moisture, said barrier means com-

prising at least a substantial amount of activated alumina.

5. An electrical heating element, comprising:
a tubular metallic sheath; a resistor in a resistor
zone within said sheath and having an end
spaced from an end of said sheath; a lead-in
conductor extending into said end of said sheath
longitudinally of said sheath and connected to
said end of said resistor; and refractory electri-
0 cal-insulating material, disposed within said
sheath, in which said resistor and said lead-in
conductor are disposed, said material in at least
a portion of said resistor zone comprising re-
fractory electrical-insulating unstable material
15 having irreversible water sorbing capacity, and
at least a transverse sectional portion of an end
zone extending from said end of said sheath to
said unstable material being occupied by a mass
of particles of refractory electrical-insulating
20 material having desired stability in the presence
of moisture and constituting barrier means for
intercepting moisture, said barrier means com-
prising at least a substantial amount of refrac-
tory electrical-insulating material having revers-
25 ible water sorbing capacity, and a transverse sec-
tional portion of said end zone intermediate said
barrier means and said unstable material being
occupied by refractory crystalline electrical-in-
sulating material substantially lacking water
30 sorbing capacity.

30 sorbing capacity.

35 6. An electrical heating element, comprising: a tubular metallic sheath; a resistor in a resistor zone within said sheath and having an end spaced from an end of said sheath; a lead-in conductor extending into said end of said sheath longitudinally of said sheath and connected to said end of said resistor; and refractory electrical-insulating material, disposed within said sheath, in which said resistor and said lead-in conductor are disposed, said material in at least 40 a portion of said resistor zone comprising refractory electrical-insulating unstable material having irreversible water sorbing capacity, and at least a transverse sectional portion of an end zone extending from said end of said sheath to 45 said unstable material being occupied by a mass of particles of refractory electrical-insulating material having desired stability in the presence of moisture and constituting barrier means for intercepting moisture, said barrier means comprising at least a substantial amount of refractory electrical-insulating material having reversible water sorbing capacity, and a transverse sectional portion of said end zone intermediate said 50 barrier means and said unstable material being occupied by refractory electrical-insulating material substantially lacking water sorbing capacity.

55

7. An electrical heating element, comprising:
60 a tubular metallic sheath; a resistor in a resistor zone within said sheath and having an end spaced from an end of said sheath; a lead-in conductor extending into said end of said sheath longitudinally of said sheath and connected to
65 said end of said resistor; and refractory electrical-insulating material, disposed within said sheath, in which said resistor and said lead-in conductor are disposed, said material in at least a portion of said resistor zone comprising crystalline magnesium oxide, and at least a transverse
70 sectional portion of an end zone extending from said end of said sheath to said portion comprising crystalline magnesium oxide being occupied by a mass of particles of refractory electrical
75 insulating material having desired stability in the

presence of moisture and constituting barrier means for intercepting moisture, said barrier means comprising at least a substantial amount of refractory electrical-insulating material having reversible water sorbing capacity.

8. An electrical heating element, comprising: a tubular metallic sheath; a resistor in a resistor zone within said sheath and having an end spaced from an end of said sheath; a lead-in conductor extending into said end of said sheath longitudinally of said sheath and connected to said end of said resistor; and refractory electrical-insulating material, disposed within said sheath, in which said resistor and said lead-in conductor are disposed, said material in at least a portion of said resistor zone comprising crystalline magnesium oxide, and at least a transverse sectional portion of an end zone extending from said end of said sheath to said unstable material being occupied by a mass of particles of refractory electrical-insulating material having desired stability in the presence of moisture and constituting barrier means for intercepting moisture, said barrier means comprising at least a substantial amount of activated alumina.

9. An electrical heating element, comprising: a tubular metallic sheath; a resistor in a resistor zone within said sheath and having an end spaced from an end of said sheath; a lead-in conductor extending into said end of said sheath longitudinally of said sheath and connected to said end of said resistor; and refractory electrical-insulating material, disposed within said sheath, in which said resistor and said lead-in conductor are disposed, said material in at least a portion of said resistor zone comprising crystalline magnesium oxide, and at least a transverse sectional portion of an end zone extending from said end of said sheath to said portion comprising crystalline magnesium oxide being occupied by a mass of particles of refractory electrical-insulating material constituting barrier means for intercepting moisture, said barrier means comprising at least a substantial amount of refractory electrical-insulating material having reversible water sorbing capacity, and a transverse sectional portion of said end zone intermediate said barrier means and said portion comprising crystalline magnesium oxide being occupied by refractory electrical-insulating material substantially lacking water sorbing capacity.

10. An electrical heating element, comprising: a tubular metallic sheath; a resistor in a resistor zone within said sheath and having an end spaced from an end of said sheath; a lead-in conductor extending into said end of said sheath longitudinally of said sheath and connected to said end of said resistor; and refractory electrical-insulating material, disposed within said sheath, in which said resistor and said lead-in conductor are disposed, said material in at least a portion of said resistor zone comprising crystalline magnesium oxide, and at least a transverse sectional portion of an end zone extending from said end of said sheath to said portion comprising crystalline magnesium oxide being occupied by a mass of particles of refractory electrical-insulating material having desired stability in the presence of moisture and constituting barrier means for intercepting moisture, said barrier means comprising at least a substantial amount of activated alumina, and a transverse sectional portion of said end zone intermediate said barrier means and said portion comprising crystalline magnesium oxide being occupied by refractory

electrical-insulating material substantially lacking water sorbing capacity.

11. An electrical heating element, comprising: a tubular metallic sheath; a resistor in a resistor zone within said sheath and having an end spaced from an end of said sheath; a lead-in conductor extending into said end of said sheath longitudinally of said sheath and connected to said end of said resistor; and refractory electrical-insulating material, disposed within said sheath, in which said resistor and said lead-in conductor are disposed said material in at least a portion of said resistor zone comprising crystalline magnesium oxide, and at least a transverse sectional portion of an end zone extending from said end of said sheath to said portion comprising crystalline magnesium oxide being occupied by a mass of particles of refractory electrical-insulating material having desired stability in the presence of moisture and constituting barrier means for intercepting moisture, said barrier means comprising at least a substantial amount of activated alumina, and a transverse sectional portion of said end zone intermediate said barrier means and said portion comprising crystalline magnesium oxide being occupied by refractory electrical-insulating material substantially lacking water sorbing capacity and consisting mainly of zircon.

12. An electrical heating element, comprising: a tubular metallic sheath; a resistor in a resistor zone within said sheath and having an end spaced from an end of said sheath; a lead-in conductor in a terminal zone, extending into said end of said sheath longitudinally of said sheath connected to said end of said resistor; and refractory electrical-insulating material, disposed within said sheath, in which said resistor is disposed, at least a transverse sectional portion of said terminal zone being occupied by a mass of particles of refractory electrical-insulating material having desired stability in the presence of moisture and constituting barrier means for intercepting moisture, said barrier means comprising at least a substantial amount of silica gel.

13. An electrical heating element, comprising: a tubular metallic sheath; a resistor in a resistor zone within said sheath and having an end spaced from an end of said sheath; a lead-in conductor extending into said end of said sheath longitudinally of said sheath and connected to said end of said resistor; and refractory electrical-insulating material, disposed within said sheath, in which said resistor and said lead-in conductor are disposed, said material in at least a portion of said resistor zone comprising refractory electrical-insulating unstable material having irreversible water sorbing capacity, and at least a transverse sectional portion of an end zone extending from said end of said sheath to said unstable material being occupied by a mass of particles of refractory electrical-insulating material having desired stability in the presence of moisture and constituting barrier means for intercepting moisture, said barrier means comprising at least a substantial amount of silica gel.

14. An electrical heating element, comprising: a tubular metallic sheath; a resistor in a resistor zone within said sheath and having an end spaced from an end of said sheath; a lead-in conductor extending into said end of said sheath longitudinally of said sheath and connected to said end of said resistor; and refractory electrical-insulating material, disposed within said

sheath, in which said resistor and said lead-in conductor are disposed, said material in at least a portion of said resistor zone comprising refractory electrical-insulating unstable material having irreversible water sorbing capacity, and at least a transverse sectional portion of an end zone extending from said end of said sheath to said unstable material being occupied by a mass of particles of refractory electrical-insulating material having desired stability in the presence of moisture and constituting barrier means for intercepting moisture, said barrier means comprising at least a substantial amount of refractory electrical-insulating material having reversible water sorbing capacity, and a transverse sectional portion of said end zone intermediate said barrier means and said unstable material being occupied by refractory electrical-insulating material substantially lacking water sorbing capacity and consisting mainly of zircon.

15. An electrical heating element, comprising: a tubular metallic sheath; a resistor in a resistor zone within said sheath and having an end spaced from an end of said sheath; a lead-in conductor extending into said end of said sheath longitudinally of said sheath and connected to said end of said resistor; and refractory electrical-insulating material, disposed within said sheath, in which said resistor and said lead-in conductor are disposed, said material in at least a portion of said resistor zone comprising refractory electrical-insulating unstable material having irreversible water sorbing capacity, and at least a transverse sectional portion of an end zone extending from said end of said sheath to said unstable material being occupied by a mass of particles of refractory electrical-insulating material having desired stability in the presence of moisture and constituting barrier means for intercepting moisture, said barrier means comprising at least a substantial amount of activated alumina, and a transverse sectional portion of said end zone intermediate said barrier means and said unstable material being occupied by refractory electrical-insulating material substantially lacking water sorbing capacity.

16. An electrical heating element, comprising: a tubular metallic sheath; a resistor in a resistor zone within said sheath and having an end spaced from an end of said sheath; a lead-in conductor extending into said end of said sheath longitudinally of said sheath and connected to said end of said resistor; and refractory electrical-insulating material, disposed within said sheath, in which said resistor and said lead-in conductor are disposed, said material in at least a portion of said resistor zone comprising refractory electrical-insulating unstable material having irreversible water sorbing capacity, and at least a transverse sectional portion of an end zone extending from said end of said sheath to said unstable material being occupied by a mass of particles of refractory electrical-insulating material having desired stability in the presence of moisture and constituting barrier means for intercepting moisture, said barrier means comprising at least a substantial amount of silica gel, and a transverse sectional portion of said end zone intermediate said barrier means and said unstable material being occupied by refractory electrical-insulating material substantially lacking water sorbing capacity.

17. An electrical heating element, comprising:

5 a tubular metallic sheath; a resistor in a resistor zone within said sheath and having an end spaced from an end of said sheath; a lead-in conductor extending into said end of said sheath longitudinally of said sheath and connected to said end of said resistor; and refractory electrical-insulating material, disposed within said sheath, in which said resistor and said lead-in conductor are disposed, said material in at least a portion of said resistor zone comprising crystalline magnesium oxide, and at least a transverse sectional portion of an end zone extending from said end of said sheath to said unstable material being occupied by a mass of particles of refractory electrical-insulating material having desired stability in the presence of moisture and constituting barrier means for intercepting moisture, said barrier means comprising at least a substantial amount of silica gel.

20. 18. An electrical heating element, comprising: a tubular metallic sheath; a resistor in a resistor zone within said sheath and having an end spaced from an end of said sheath; a lead-in conductor extending into said end of said sheath longitudinally of said sheath and connected to said end of said resistor; and refractory electrical-insulating material, disposed within said sheath, in which said resistor and said lead-in conductor are disposed, said material in at least a portion of said resistor zone comprising crystalline magnesium oxide, and at least a transverse sectional portion of an end zone extending from said end of said sheath to said portion comprising crystalline magnesium oxide being occupied by a mass of particles of refractory electrical-insulating material having desired stability in the presence of moisture and constituting barrier means for intercepting moisture, said barrier means comprising at least a substantial amount of silica gel, and a transverse sectional portion of said end zone intermediate said barrier means and said portion comprising crystalline magnesium oxide being occupied by refractory electrical-insulating material substantially lacking water sorbing capacity.

45. 19. An electrical heating element, comprising: a tubular metallic sheath; a resistor in a resistor zone within said sheath and having an end spaced from an end of said sheath; a lead-in conductor extending into said end of said sheath longitudinally of said sheath and connected to said end of said resistor; and refractory electrical-insulating material, disposed within said sheath, in which said resistor and said lead-in conductor are disposed, said material in at least a portion of said resistor zone comprising crystalline magnesium oxide, and at least a transverse sectional portion of an end zone extending from said end of said sheath to said portion comprising crystalline magnesium oxide being occupied by a mass of particles of refractory electrical-insulating material having desired stability in the presence of moisture and constituting barrier means for intercepting moisture, said barrier means comprising at least a substantial amount of silica gel, and a transverse sectional portion of said end zone intermediate said barrier means and said portion comprising crystalline magnesium oxide being occupied by refractory electrical-insulating material substantially lacking water sorbing capacity and consisting mainly of zircon.
